US00D700250S

(12) **United States Design Patent**
Martino et al.

(10) **Patent No.:** US D700,250 S
(45) **Date of Patent:** ** Feb. 25, 2014

(54) **TOY VEHICLE**

(71) Applicant: **Mattel, Inc.**, El Segundo, CA (US)

(72) Inventors: **Anthony M. Martino**, Thousand Oaks, CA (US); **Kevin Kai Cao**, Reseda, CA (US)

(73) Assignee: **Mattel, Inc.**, El Segundo, CA (US)

(**) Term: **14 Years**

(21) Appl. No.: **29/450,465**

(22) Filed: **Mar. 18, 2013**

Related U.S. Application Data

(62) Division of application No. 29/397,875, filed on Jul. 21, 2011, now Pat. No. Des. 681,742.

(51) **LOC (10) Cl.** **21-01**

(57) **CLAIM**

We claim the ornamental design for a toy vehicle, as shown and described.

DESCRIPTION

FIG. 1 is a top, front, and right side perspective view of the toy vehicle;

FIG. 2 is a top, rear, and left side perspective view thereof; FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines shown in the drawings illustrate portions of the toy vehicle that form no part of the claimed design.

1 Claim, 3 Drawing Sheets
